Mario J. Piraino, Pittsburgh, Pa.

Application June 13, 1945, Serial No. 120,057

Term of patent 7 years

(Cl. D29—23)

To all whom it may concern:

Be it known that I, Mario J. Piraino, a citizen of the United States, residing in Pittsburgh, in the county of Allegheny and State of Pennsylvania, have invented a new, original, and ornamental Design for a Display Plaque or Similar Article, of which the following is a specification, reference being had to the accompanying drawing, forming part thereof.

I claim:

The ornamental design for a display plaque or similar article, substantially as shown.

MARIO J. PIRAINO.
